UNITED STATES PATENT OFFICE.

HALSEY W. TAYLOR, OF WARREN, OHIO.

DRINKING FOUNTAIN.

Application filed June 6, 1927. Serial No. 196,728.

My invention relates to an improvement in drinking fountains, especially a drinking fountain of the kind and type shown in my Letters Patent of the United States, No. 5 1,624,081, dated April 12, 1927, in which a floating weight or plunger is utilized to vent a part of the water supply and maintain an arched drinking stream or column of water in a fixed shape regardless of fluctuations in 10 the supply. The present improvement is designed to yield the same results as stated, but structurally the present device is simpler and more compactly arranged and constructed and the floating weight itself is utilized to 15 form and deliver the arched drinking stream. Briefly stated, the present improvement comprises a water balancing weight or floating vent member which also functions as a stream forming nozzle or delivery spout when loosely 20 confined within a fountain head or hollow body adapted to be connected to a valve-controlled source of water supply.

In the accompanying drawings, Fig. 1 is a 25 sectional view of a drinking fountain head embodying the invention, and Fig. 2 is a side elevation thereof. Fig. 3 is a horizontal section of the fountain head on line 3—3 of Fig. 1. Figs. 4, 5, and 6, are sectional views of the 30 fountain head cap, the combined balancing weight and nozzle member, and the main body of the attachment, respectively. Fig. 7 is a sectional view of a modification showing a double stream projector. Fig. 8 is a sectional view of another modification of the invention, 35 and Fig. 9 is a horizontal section on line 9—9 of Fig. 8.

The present device comprises a tubular body 2 having a reduced screw-threaded stem or extension 3 adapted to connect with a 40 water supply fitting or pipe not shown, but which it should be understood, may include or contain a valve to control the outflow of water for drinking purposes, together with adjustable means adapted to regulate the 45 pressure and maintain an arched drinking stream of substantial height. Figs. 1 to 6 show the upper end of body 2 screw-threaded exteriorly to permit a cap or cover 4 to be detachably connected thereto. Preferably, 50 the screw-threads 5 are mutilated or of segmental character or kind to provide vertical drain passages 6 at the outer side of body 2, and the flat top 7 of cap 4 is horizontally inclined and contains a round opening 8 through which the drinking stream is 55 discharged vertically at a steep inclination. The

upper end of body 2 contains a circular chamber 9 having a bead or annular valve seat 10 at its bottom surrounding the main water intake passage 11, and a round cylindrical element 12 of a predetermined size and weight is loosely confined within chamber 9 and formed with an annular depression 13 at its bottom adapted to rest upon the bead or annular seat 10 when the water is shut off, or 60 the pressure is so reduced that the force of the water against the bottom of element 12 is entirely overcome by the weight of such element. A vertically-inclined passage or outlet port 14 extends through element 12 65 axially in line with opening 10 in cap 7, and a pin 15 projects into a vertical passage 16 in the wall of body 2 and holds the element in that aligned position. The intake end of port 14 is located centrally of the annular 70 valve seat 10 at the upper end of circular chamber 9, and the water is free to escape through port 14 at all times. The water is also free to escape laterally from beneath the floating weight or element 12, whenever this 75 weight or element is raised apart from valve seat 10. Vent openings 17 in the side wall of chamber 9 are opened more or less when element 12 is raised more or less. Such variable movement of element 12 occurs when fluctuation in the water pressure takes place. The 80 pressure and volume of water being known and the device designed and set accordingly the water is discharged through port 14 and thereby formed into an arched drinking 85 stream of a predetermined height. If the volume or pressure of water is increased beyond this normal working condition the stream-forming element 12 is raised and the 90 water vents through side openings 17, and the drinking column is not substantially altered in shape and form; spouting of water, in turning 95 on the stream initially, is also prevented.

In Fig. 7 I show a fountain head of the same general structure as described, excepting that a combined weight and stream-forming element 18 contains two ports 19 and 20 adapted to project two separate streams into confluence to form a single arched drinking stream.

In Figs. 8 and 9, I show a modification comprising a flanged body 21 having radial ribs 22, and a weighted stream forming element 23 seated loosely thereon, the said weight or element having an inclined port 24 in its top to 100 form the drinking stream and a flange or skirt 25 adapted to confine the element in 110

place upon body 21. A pin 26 in flange 25 limits the movement of element 23 vertically and rotatably.

What I claim is:

- 5 1. A drinking fountain fitting or head, comprising a body having a water supply passage and a vent opening, and a weighted element movably seated and adapted to control the flow of water through said vent opening while constantly exposed to the pressure of the water within the supply passage, said movable element having an opening therein communicating with said supply passage of the body for jetting water vertically for drinking purposes.
- 10 2. A drinking fountain fitting or head, comprising a body having a water supply passage, a vent opening and valve seat, and a weighted element loosely seated upon said valve seat adapted to control the amount of water flowing through said vent opening, said weighted element having an inclined passage in communication with said supply passage and adapted to jet a stream of water upwardly at an inclination to form an arched drinking stream.
- 15 3. A drinking fountain fitting or head, comprising a body having a water supply passage and vent openings, a weighted element loosely seated upon said body opposite said vent openings and constantly exposed to the pressure of water within said passage and shiftable by water pressure to permit venting of water through said vent openings, said element having an outlet port therein in communication with said supply passage and adapted to jet a part of the water upwardly, and means adapted to confine said element upon said body.
- 20 4. A drinking fountain fitting or head, comprising a body having a water supply passage, a weighted member loosely confined upon said body opposite said passage and exposed to the water in said passage, said member having a discharge orifice communicating with said passage and adapted to form a drinking stream, and a guiding member cov-

ering said weighted member having a water escape opening opposite said orifice in the weighted member and an open bottom for open communication of said supply passage with the open air, when by water pressure said weighted member is raised with respect to said body.

5. A drinking fountain fitting or head, comprising a body having a chamber formed with vent openings and a valve seat and a water supply passage, a weighted element loosely seated within said chamber upon said valve seat and adapted to be shifted by water pressure for open communication between said supply passage and said vent openings, said element having a water passage communicating with said supply passage and adapted to form a drinking stream, a cover for said chamber having an opening in line with the water passage of said weighted element, and means adapted to secure said parts together.

6. A drinking fountain fitting or head, comprising a hollow body having a chamber and a valve seat therein and formed with mutilated screw-threads exteriorly thereof, a weighted element loosely seated within said chamber upon said valve seat having a water discharge passage vertically therein, and a cover screw-connected with said body having a water escape opening in its top opposite the passage in said element.

7. A drinking fountain fitting or head, comprising a body having a water supply passage and a vent opening, and a weighted element seated upon said body controlling said vent opening and constantly exposed to the water-pressure within said supply passage, said element having a water passage communicating with said supply passage, and said element being adapted to be shifted by water pressure for venting of surplus water supply through said vent opening when discharging a stream of water constantly therefrom.

In testimony whereof I affix my signature.

HALSEY W. TAYLOR.

CERTIFICATE OF CORRECTION.

Patent No. 1,715,875.

Granted June 4, 1929, to

HALSEY W. TAYLOR.

It is hereby certified that error appears in the printed specification of the above numbered patent requiring correction as follows: Page 2, after line 3, insert the following "The spacing ribs 22 formed radially of body 21 separate or space the flange or skirt 25 apart from the sides and top edge of the body, thereby forming venting spaces for this modified form of fountain head".; same page, line 47, claim 4, strike out the word "guiding"; and that the said Letters Patent should be read with these corrections therein that the same may conform to the record of the case in the Patent Office.

Signed and sealed this 2nd day of July, A. D. 1929.

(Seal)

M. J. Moore,
Acting Commissioner of Patents.
